DISPENSER COVER FOR A PRESSURIZED CONTAINER

John C. Louise, Englewood, N.J., assignor to Clairol Incorporated, New York, N.Y.

Filed May 12, 1971, Ser. No. 142,854

Term of patent 14 years

Int. Cl. D9—07
U.S. Cl. D9—258

FIG. 1

FIG. 2

FIG. 3

FIG. 1 is a front perspective view of a dispenser cover for a pressurized container embodying my new design;

FIG. 2 is a rear perspective view; and

FIG. 3 is a side perspective view thereof;

The broken lines showing a pressurized container in each figure are for illustrative purposes only.

I claim:

The ornamental design for a dispenser cover for a pressurized container, substantially as shown and described.
